UNITED STATES PATENT OFFICE.

EDMOND F. DAILY, OF ANDERSON, INDIANA.

DESIGN FOR A REIN-HOLDER.

SPECIFICATION forming part of Design No. 20,447, dated January 6, 1891.

Application filed November 5, 1890. Serial No. 370,433. Term of patent 14 years.

To all whom it may concern:

Be it known that I, EDMOND F. DAILY, a citizen of the United States, residing at Anderson, in the county of Madison and State 5 of Indiana, have invented a certain new and useful Design for Rein-Holders; and I do hereby declare the following to be a full, clear, and exact description of the invention, such as will enable others skilled in the art to which it applies to make and use the same.

The figure illustrates a perspective view of my rein-holder.

A represents a loop having the arms A' and A², which are bent to the rear of the loop and then curved downward and outward from each other, substantially as shown in the drawing. The lower ends a' and a², respect-

ively, may be formed in any desired way, as they form no part of my design; but I prefer to have the ends flattened and perforated, as 20 shown, however, and therefore include them in the drawing.

The loop A may be provided with an opening a.

What I claim as new is--

The design substantially as shown and described.

In testimony whereof I affix my signature in presence of two witnesses.

EDMOND F. DAILY.

Witnesses:

E. R. CHENEY,
L. L. LANGELL.
